UNITED STATES PATENT OFFICE.

FREDERICK A. BURTON, OF NEW YORK, N. Y.

BOTTLE CAP.

1,427,259.

Specification of Letters Patent. Patented Aug. 29, 1922.

Application filed January 27, 1922. Serial No. 532,176.

To all whom it may concern:

Be it known that I, FREDERICK A. BURTON, a citizen of the United States, and a resident of the borough of Manhattan, city, county, and State of New York, have invented certain new and useful Improvements in Bottle Caps, of which the following is a specification.

My invention relates to an improved cap 10 for thermos bottles, which consists in a plurality of cups of like shape, the inner cap being secured to the thermos bottle, as well known in the art, and the series of outer caps being respectively secured to each 15 other and the inner cap so as to provide a cap which may be formed of a series of telescopic cups, all of which may be secured in place and may be readily detached from the thermos bottle and used separately as cups.

20 In the drawings:

Fig. 1 is an elevation of a thermos bottle of ordinary type constructed to receive a cap structure embodying my invention.

Fig. 2 is an elevation of a thermos bottle 25 provided with a plurality of cup shaped caps secured to the structure as shown in Fig. 1.

Fig. 3 is a vertical section, partly in elevation, of an enlarged view of an upper 30 portion of a thermos bottle and cap structure embodying my invention.

It is well known that thermos bottles are conveniently carried by parties consisting of several persons when traveling or when going 35 on picnics and the cap ordinarily applied to the top of the bottle to cover the sealing cork is utilized as a cup in drinking the contents of the thermos bottle. As the bottles are now constructed, it is necessary to 40 use a single cup for the use of several persons and this is not always found to be entirely convenient and satisfactory. Picnic parties sometimes carry a series of paper cups, commonly called "Lily" cups, or 45 other cups of like nature, but these cups are merely intended for use once or twice, and their life is short and they have to be thrown away.

My invention consists in not only forming a cap for the thermos bottle in substantially the manner now in vogue, but this cap is made up of a series or plurality of similarly cup shaped elements, each of which is provided near its outer edge or 55 mouth with fastening means which consist preferably of screwthreads so that the de-

pressions or grooves of the screwthreads on the inner surface of the mouth of the cup form the ridges or ribs of the screwthread on the outer side of the cup and vice versa.

The cup shaped elements are each of substantially the same size and made of material of the same thickness, preferably metal, so that one cup will fit into and be 65 closely nested with the other and the entire series so nested can be secured to the screwthreads on the neck of the thermos bottle in the manner now in vogue.

In the drawings, A is a thermos bottle, B 70 the neck, C a cup shaped cap consisting of a series of cups, c' and c^2 , c^3 and c^4 , though it is to be understood the number of cups comprising the series may be as many as desirable and within reason.

75 The neck of the thermos bottle has the usual stopper S inserted therein and is provided with a screwthreaded surface 10, all as well understood. The inner cup c' or cap consists of a cup portion 11, the outer edge 80 of which is provided with a pressed up screwthreaded surface 12, having a series of inner depressions and projections 13 and a series of complementary depressions and projections on the outside thereof, as at 14, all 85 formed by compressing or stamping the said screwthreads in the inner and outer surface of the mouth portion of the cup.

The inner series of screwthreads are arranged to engage with the screwthreads 10 90 formed on the neck B of the thermos bottle, and the outer series of screwthreads at 14 are in position to engage the inner screwthreads 23 of the adjacent cup portion c^2 , the outer screwthreads 24 on said cup portion c^2 95 engaging the inner screwthreads 33 upon the cup portion c^3 , and the outer screwthreads 34 engaging the inner screwthreads 43 of the cup portion c^4 , leaving the outer screwthreads 44 for engagement with the 100 screwthread on an adjacent cup portion, if desired.

105 The cups, if desired, are provided at their respective mouths with lips 50, 51, 52 and 53, as shown.

The threaded portions of the cups are enlarged or offset from the cup portions by means of flange portions 60, 61, 62 and 63 respectively to prevent the inner ridges of the screwthreads from contacting with the 110 outer surfaces of the cups as they are assembled.

By means of the construction above described, a sufficient number of cups may be conveniently carried and used by a party of several persons, each having the benefit of an 5 individual cup.

The metal cup-shaped elements forming the cap may be finished smooth, as well known, in order to make the bottle when closed more attractive.

10 As changes of construction could be made within the scope of my invention, it is intended that all matter contained in the above description or shown in the accompanying drawing shall be interpreted as illustrative 15 and not in a limiting sense.

Having thus described the invention, what I claim as new and desire to secure by Letters Patent is:

1. A cap for thermos bottles which 20 comprises a number of cup members adapted to telescope on each other and having interlocking screwthreaded portions, said screwthreaded portions being enlarged or offset from the walls of the cups to prevent interference of the screwthreads with the surfaces 25 of the cups.

2. A cap for thermos bottles which comprises a number of cup members having external and internal screwthreads adapted to permit said cup members to be nested and 30 secured together to form a unitary cap the dimensions and shape of the body and screwthreaded portions being such that the cups may be screwed to each other or any individual cup may be screwed to the bottle. 35

3. A device of the kind described which comprises a bottle having a screwthreaded surface on its neck and a cap for said bottle adapted to screw directly onto said neck said cap comprising a number of cup members 40 adapted to telescope on each other and having interlocking screwthreaded portions, said screwthreaded portions being enlarged or offset from the walls of the cups to prevent interference of the screwthreads with 45 the surfaces of the cups.

In witness whereof, I have hereunto set my hand at the borough of Manhattan, city and State of New York, this 23 day of January, 1922.

FREDERICK A. BURTON.
